US0D1104953S

(12) **United States Design Patent** (10) Patent No.: **US D1,104,953 S**
(45) Date of Patent: ** Dec. 9, 2025

(54) **RECHARGEABLE BATTERY**

(71) Applicant: **Jianwei Liu**, Shenzhen (CN)

(72) Inventor: **Jianwei Liu**, Shenzhen (CN)

(**) Term: **15 Years**

(21) Appl. No.: **29/958,112**

(22) Filed: **Aug. 17, 2024**

(51) LOC (15) Cl. **13-02**

(52) U.S. Cl.

USPC **D13/103**

(58) **Field of Classification Search**

Primary Examiner — Christy Nemeth

(57) **CLAIM**

The ornamental design for a rechargeable battery as shown and described.

DESCRIPTION

FIG. 1 is a front, left and top perspective view of a rechargeable battery showing my new design;

FIG. 2 is a rear, right and bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The evenly broken lines illustrate portions of the rechargeable battery that form no part of the claimed design.
